SHOCK-ABSORBING SUPPORT FOR RADIO-TUBE MOUNTS

Walter L. Krahl, Swampscott, Mass., assignor to
Hygrade Sylvania Corporation, Salem, Mass.,
a corporation of Massachusetts

Application March 10, 1937, Serial No. 129,993

6 Claims. (Cl. 250—27.5)

This invention relates to electric discharge tubes and more particularly to shock-absorbing supports for the electrode assembly or mount of a radio tube and the like.

5 A principal object of the invention is to provide a simple, inexpensive and thoroughly reliable shock-absorbing support for a radio tube mount.

A feature of the invention relates to a flexible wire clip which is readily attachable as by welding, to an electrode side-rod or other similar part 10 of a radio tube mount.

15 Other features and advantages not specifically enumerated will be apparent after a consideration of the following detailed description and the appended claims.

In the drawing,

Fig. 1 is an elevational view, partly in section, of a radio tube embodying the invention.

Fig. 2 is a top plan view of the mount of 20 Fig. 1.

While the invention will be illustrated as embodied in one well-known form of radio tube having a glass enclosing envelope, it will be understood that it is not limited thereto but is also 25 applicable to so-called metal tubes. Likewise since the invention is not concerned with any particular number or arrangement of electrodes in the mount, only sufficient parts of a mount are shown to enable the invention to be understood. Accordingly, in Fig. 1 the numeral 1 represents a glass enclosing envelope preferably of the ST shape, that is with a cylindrical dome portion 2 at the top. Sealed into the envelope 1 is a reentrant stem or base 2 wherein are insulatingly 30 supported the various lead-in and support wires 4 to 10 inclusive. The mount or electrode assembly may comprise any number of electrodes but merely for purposes of explanation a mount of the triode type is shown, and comprises an indirectly heated cathode 11, a grid 12 supported on the side-rods 13, 14, and a tubular plate or anode 15 supported on the side-rods 4 and 10. For the purpose of maintaining the spacial relation of the various electrodes, upper and lower insulator 40 spacer members 16 and 17 are provided, these spacer members being of mica, ceramic or the like and having a series of perforations as shown in Fig. 2 to receive the ends of the various side-rods as well as the ends of the cathode sleeve and said spacers being secured to the support rods 4 and 10 as by eyelets 25. Preferably the mount is supported so that it extends partly within the cylindrical or dome portion of the bulb.

As shown clearly in Fig. 1, the plate side-rods 55 4 and 10 extend upwardly beyond the upper

spacer member 16 and in order to support the upper end of the mount in a shock-proof manner from the dome 2, there are provided two flexible wire clips 18, 19 of phosphor-bronze or similar spring metal. Each of the said clips is provided 5 intermediate its ends with an offset portion 20 which is adapted partially to surround the upper end of the associated plate side-rod. Preferably the clips are fastened to the side-rods by welding thereto at the said offset portions. As shown each clip is welded to its side-rod so that the offset portion 20 is inclined at an angle of approximately 45 degrees to the vertical axis of the mount, and preferably so that the two legs 21, 22 of each offset, engage the edge of the mica spacer 16. 10 The free end portions of each clip, when the mount is assembled within the bulb, extend outwardly beyond the mica and being normally longer than the space between the edge of the mica and the inner wall of the dome 3, are flexed 15 to a substantially vertical position as shown in Fig. 1 so as to conform themselves to the shape of the dome. Preferably, although not necessarily, the said free ends are rounded and slightly curved inwardly towards each other. It will be 20 understood of course that the clips are welded to the plate side-rods prior to assembling the mount within the bulb so that the said clips center the mount with respect to the bulb, but are not disturbed during the usual "pull-down" operation 25 of sealing the mount into the bulb. By this arrangement, therefore, the wire clips each provide a pair of flexible supports for the upper end of the mount with respect to the bulb, and the ends 23, 24 adapt themselves readily to bulbs of different 30 diameters. Furthermore, the legs 21, 22 of each clip are normally of more uniform stiffness than mica springs, and the mounts will therefore be more accurately centered in the domes 3 of the bulbs 1. 35

40 Various changes and modifications may be made in the disclosure without departing from the spirit and scope of the invention.

What I claim is:

1. In combination an enclosing envelope having a cylindrical portion, an electrode assembly mounted within the envelope and extending at least partially into said cylindrical portion, said assembly having a pair of spaced vertical uprights, an electrode spacer of insulating material 50 bridging the upper ends of said uprights and means to resiliently support said assembly in spaced relation to said cylindrical portion the last-mentioned means comprising a pair of metal springs each having an offset portion embrac- 55

- ing and welded to an associated one of said side-
5 rods with portions intermediate the ends en-
gaging the edge of said insulator spacer and with
the end portions in contact with said enclosing
envelope.
2. In combination an enclosing envelope hav-
ing a cylindrical portion, a radio tube mount
within said envelope and extending at least part
way into said cylindrical portion, said mount in-
10 cluding an insulating electrode spacer extending
transversely across said cylindrical portion and a
pair of side-rods extending through said spacer,
and means to resiliently support said mount in
spaced relation to said cylindrical portion, the
15 last-mentioned means comprising a pair of bi-
furcated wire springs each having an offset por-
tion fastened to an associated one of said side-
rods, said springs being inclined downwardly at
an angle to said side-rods and having their bi-
20 curcated ends in contact with the said cylindrical
portion.
3. In combination an enclosing envelope having
a cylindrical portion, a radio tube mount within
25 said envelope and extending at least part way
into said cylindrical portion, said mount includ-
ing an insulating electrode spacer extending
transversely across said cylindrical portion and a
pair of side-rods extending through the spacer,
30 and means to resiliently space said mount from
the cylindrical portion of the envelope, the last-
mentioned means comprising a pair of bi-furcated
metal springs each having an offset portion fas-
tened to an associated one of said side-rods, each
35 spring being inclined downwardly with respect
to the mount and being retained in flexed form
by having the bi-furcated portions in engagement
with the edge of the spacer and the free ends in
contact with the said cylindrical portion.
4. In combination, an enclosing envelope hav-
40 ing a cylindrical portion at its upper end, a radio
tube mount within said envelope and extending
at least part way into said cylindrical portion,
said mount including a disc of insulation extend-
ing transversely across said cylindrical portion
45 and a pair of side rods extending through said
- spacer to support the same, and means to re-
siliently space said mount from the envelope, the
last-mentioned means comprising a pair of metal
springs each spring being fastened to a corre-
sponding side rod and having a portion inter-
5 10 mediate its ends in engagement with the edge of
said disc and the two ends of each spring ex-
tending beyond said disc into engagement with
said cylindrical portion, said springs being re-
tained in flexed condition by reason of their en-
gagement with the disc edge and the said cyl-
indrical portion.
5. In combination, an enclosing envelope hav-
ing a cylindrical portion at its upper end, a radio
tube mount within said envelope and extending
15 at least part way into said cylindrical portion,
said mount including a disc of insulation extend-
ing transversely across said cylindrical portion
and a pair of side rods extending through said
20 spacer to support the same, and means to re-
siliently space said mount from the envelope, the
last-mentioned means comprising a pair of metal
springs at opposite sides of said disc each spring
25 having its central portion fastened to one of said
side rods and having a portion intermediate its
ends in engagement with the edge of said disc,
the two ends of each spring extending beyond
30 the disc into engagement with said cylindrical
portion, said springs being retained in flexed con-
dition by reason of the engagement with the edge
of the disc and said cylindrical portion.
6. In a radio tube, an electrode assembly unit
supported within the tube and mounted above a
pair of support wires, said unit including a spacer
35 strip threaded over said wires, and a pair of cen-
tering and supporting metallic springs, each hav-
ing off-set portions intermediate the ends and
fastened to a different one of said support wires,
each spring having flexible end portions extend-
40 ing outwardly beyond the electrode assembly and
into engagement with the interior wall of the
tube, each of said springs also engaging a corre-
sponding edge of said strip.
